CAB AND BODY STRUCTURE FOR AN EXCAVATOR

Robert B. Kennicutt, Morton, and Ellis A. Sifton, East Peoria, Ill., assignors to Caterpillar Tractor Co., Peoria, Ill.

Filed Apr. 27, 1973, Ser. No. 355,192

Term of patent 14 years

Int. Cl. D15—04

U.S. Cl. D40—5

III - 3 -

III - 4 -

- 5 -

FIG. 1 is an elevational view of one side of the cab and body structure for an excavator embodying our new design;

FIG. 2 is an elevational view of the opposite side thereof;

FIG. 3 is a front elevational view thereof;

FIG. 4 is a rear elevational view thereof; and

FIG. 5 is a top plan view thereof.

We claim:

The ornamental design for a cab and body structure for an excavator, substantially as shown.
